UNITED STATES PATENT OFFICE.

JOHN S. WORTH, OF COATESVILLE, PENNSYLVANIA, ASSIGNOR OF ONE-HALF TO
WILLIAM P. WORTH, OF COATESVILLE, PENNSYLVANIA.

MACHINE FOR SHAPING METAL PLATES.

1,003,849.

Specification of Letters Patent. Patented Sept. 19, 1911.

Application filed May 20, 1908. Serial No. 433,865.

To all whom it may concern:

Be it known that I, JOHN S. WORTH, a citizen of the United States, residing in Coatesville, Pennsylvania, have invented certain Improvements in Machines for Shaping Metal Plates, of which the following is a specification.

The object of my invention is to construct a machine for rapidly and accurately shaping metal plates.

My invention is especially adapted for making a very deep dish in large plates, although the invention is applicable for other uses.

In the accompanying drawings:—Figure 1, is a vertical sectional view on the line 1—1, Fig. 3, of my improved machine; Fig. 2, is a vertical sectional view on the line 2—2, Fig. 3; Fig. 3, is a plan view on the line 3—3, Fig. 4; Fig. 4, is a vertical sectional view on the line 4—4, Fig. 3, showing the central part of the machine omitted; Fig. 5, is a plan view of the upper portion of the machine; Fig. 6, is a plan view of the dished former; Figs. 7, 8 and 9, show different steps in the process of dishing a plate; Figs. 10 and 11, are views showing the steps and the methods of making the flanged opening in the dished plate; Fig. 12, is a sectional view of a plate dished, cut and flanged by my improved machine; Fig. 13, is a detail view of the water supply pipe leading to the central movable cylinders; Fig. 14, is a diagram perspective view showing the counterbalance mechanism; Fig. 15, is a view of a portion of the counterbalance mechanism; Fig. 16, is an enlarged view of the upper head of the machine; Fig. 17, is an enlarged view of the lower head of the machine; Fig. 18, is a diagram view showing the paths of the different rolls; Fig. 19, is a view of the water supply pipes leading to the two side cylinders; and Fig. 20, is an enlarged view showing the corrugated flange of the former.

Before explaining the details of the machine I will describe in general its operation.

A flat plate previously heated, preferably having a perforation in the center, is placed in position in the machine over a central pin and resting on the flanges of a dished former. Two sets of pressure rolls are used to force the body of the plate gradually into the former, and rolls above the flanges

of the former tend to keep the edges of the plate down upon the flanges and as the plate is dished there are vertically arranged rolls which prevent buckling of the edges of the plate.

After the plate has been forced down so as to conform to the shape of the former, and if it is desired to make an opening in the plate, a central cutter is used which cuts a disk out of the bottom of the dished plate and then a flange may be formed, if desired, by continuing the downward movement of the head, the flange is turned outward on the dished plate, as clearly shown in the sectional view, Fig. 12. The plate is preferably dished in two heats; the plate being partially dished on the first heat and after it is reheated it is completely dished, as shown, although in some instances a plate may be dished with a single heat.

Referring in the first instance to Figs. 1 to 5, inclusive, A, A are the standards which are mounted on suitable foundations and supporting the transverse beams B. A', A' are extensions of the standards supporting the top frame B'. B², B² are heavy beams extending transversely from one standard A to the other directly above the foundation, and these beams support the mechanism of the dished former which forms the lower die of the machine.

I will first explain the mechanism for supporting and operating the dished former. The transverse beams B² have depending saddles B³ and a bearing b extends from one beam B² to the other and a step bearing b' is carried by the saddles. Mounted in the bearings is a hollow shaft C having an annular flange c near its upper edge supporting the head C' to which is secured the dished former D. This former has a central opening as shown, so that a hole can be punched in the dished plate and flanged by the mechanism described hereafter. On the upper edge of the former is a flange d upon which the plate to be punched is placed. This flange is preferably made separate from the former as illustrated in the large figures of the drawings.

The shaft C is driven from a driving shaft C² through a pinion c' and a gear wheel c². The lower end of the shaft is adapted to a step bearing b' of any ordinary type, in the present instance rings on the bearing are adapted to grooves on the shaft. Extending

100

105

110

through the center of the shaft is a vertical adjustable rod E carrying a pin e at its upper end. This pin has a screw threaded shank adapted to a threaded opening in the end of the rod. Also carried by this rod E is a head E' supporting a series of rings e', e². The inner ring e² has a head e³ and it has a flange resting upon the reduced portion of the head E', as clearly shown in Fig. 11. This head e³ forms the lower cutter of the shears for cutting the plate. The vertically arranged rings e' carry an annular head e⁴ which acts as a filler between the edge of the dished former D and the cutter head e³. When it is desired to make openings of different diameters in the dished plate the head and the rings e⁴ can be removed and others of different sizes substituted for them without dismantling the machine.

The rod E and its head E' are arranged to move vertically and this vertical movement is accomplished through a plunger E² extending through the lower bearing b' of the shaft C and bearing upon the end of the rod E. The lower end of this plunger is adapted to a cylinder E³ which is suspended from the saddle B³, as shown clearly in Figs. 1 and 2. This cylinder in the present instance is a hydraulic cylinder and water under pressure is admitted to the cylinder through the controlling mechanism within easy reach of the operator, so that when it is desired to lift the head E' water is admitted to the cylinder and the plunger is forced upward, carrying with it the rod and head, and the head can be lowered to any degree desired by allowing the water to escape from the cylinder. The head is raised to bring the pin above the line of the plunger of the dished former so that the plate with the central perforation can be placed over the pin, thus bringing it central in respect to the former, after which it is gradually lowered as the plate is dished. After the plate is completely dished then the head E' is raised for the purpose of forcing the finished plate out of the dished former, so that it can be readily removed from the machine and it is also used when the plate is removed for the reheating, when necessary.

Carried by the transverse beams B is a hydraulic cylinder F in which is a plunger F' having a reduced portion F² which extends through a stuffing box in the cap f of the cylinder F. Mounted on the lower end of the plunger F' is a head G and this head has a flange g which is shaped to conform to the finished plate, as shown in Fig. 11. The connection of this head is such as to allow it to freely turn on the end of the plunger and also carried by the plunger is a frame G' having arms which carry two conical rollers g' which press upon the plate and aid in dishing it.

On the end of the extension F² is a cross head f' connected by rods f² to a cylinder F³ in which is a plunger h connected to a rod H extending through the plunger F' and extension F² and coupled to a cutter head H' having an annular flange h' provided with a knife which operates in conjunction with the head e³ to shear the plate and form the opening therein. The back of the flange of the head to which the knife is secured is rounded and forms the upper die for flanging the plate after the opening is cut, as clearly shown in Fig. 11.

In order to retract the plunger F' and the mechanism carried by it, I provide a cross head I which is secured to the rod H between two flanges on the rod and this cross head is connected to plungers i adapted to cylinders I', one on each side of the main cylinder F, as clearly illustrated in Fig. 2.

Water under pressure is admitted to the several cylinders through valves placed in easy reach of the operator. On each side of the main cylinder F is a slide J adapted to ways on the beam B and the slides are operated in unison by a screw shaft J' adapted to bearings in brackets on the beam B and driven preferably by an electric motor through suitable reverse gearing, so that the slides can be moved toward and from the main cylinder F.

Carried by the slides J are guide frames J² supporting hydraulic cylinders J³ and adapted to each cylinder is a plunger K having an extension K', said extension being forked at the lower end and carrying a swivel bearing k for the presser roller k'. The periphery of these presser rolls is curved as shown so as to conform to the finished plate, as illustrated in Figs. 7 and 9.

As soon as water under pressure is exhausted from the cylinders J³ counterweights L return the plungers and the rolls k' to the raised position clear of the dished former. The detail construction of the counterweight mechanism will be described hereafter.

Mounted on the foundation are radial guide frames M, four in the present instance, as shown in Figs. 3, 4 and 5, on each of which is mounted a slide N. A feed screw m is adapted to bearings in the frame M and to a nut m' mounted on the carriage N, so that on turning this feed screw the carriage is moved toward and from the center of the machine. The feed screws m are geared together so that they will turn in unison, the gearing being similar to the gearing by which the several shafts n and p are driven, as illustrated in Fig. 3.

M' is a fixed standard secured to the rear of each frame M and arranged to support the rear ends of the shafts n and p.

Adapted to move vertically on the slide N is a carrier N' having a stud n' on which is

mounted the roller n^2 which is arranged to press the plate down upon the flange of the dished former. This carrier can be vertically adjusted by means of a screw n^3 5 geared to the shaft n and driven by any suitable mechanism, preferably by an electric motor, and the shafts n are coupled by shafts n^4 so that they will work in unison, although they may be driven independently if desired. Also mounted on the slide N is a carrier P having a bracket p' carrying a vertical stud p^2 on which is mounted a roller p^3 of the shape clearly illustrated in Figs. 4 and 9. This roller is arranged to 10 press upon the inner edge of the partially dished plate so as to force it against the dished former and prevent it from buckling as it is being forced into the former, and the carrier P can be raised and lowered by 15 a screw shaft p^4 which engages the nut on the carrier and is driven by the shaft p from an electric motor or other power.

Thus it will be seen that the two series of rollers n^2 and p^3 can be controlled at will so as to keep tension on the plate and prevent it buckling. In practice the several shafts p 20 are geared together by shafts p^5 and operated from a single electric motor, the switch of which is placed within easy reach 25 of the operator as is also the switch mechanism for turning the current on the motor controlling the shaft n as well as the shaft m for causing the slides to move to and from the center of the machine.

30 When it is wished to center a plate in the machine, which is not perforated, I may use the rollers p^3 or rollers n^4 on the carriers N , Fig. 4.

In order to allow for the adjustment of 40 the cylinders J^2 toward and from the center of the machine, so as to bring the rolls k' in proper relation to the dished former, I mount two cylindrical casings R , Fig. 19, on the upper cross beam B' and freely passing through each casing is a tube r . Stuffing 45 boxes are located at each end of each cylinder so as to prevent the escape of water under pressure. Each tube has an opening as at r' so as to form a communication between the interior of the tube and the interior of the cylindrical casing. The tube is 50 connected to a tubular bracket r^2 attached to one end of a cylinder J^2 , so that if the cylinder is moved toward and from the center of the machine the tube r will slide freely in the cylindrical casing R . By this means 55 I am enabled to make a fixed connection between the cylindrical casings and the water supply pipe which extends to a point within 60 easy reach of the operator.

In order to properly balance the rollers k' and the carriers K' and plunger, I provide the mechanism which is clearly illustrated in Figs. 1, 14 and 15. On the portions J^3 of 65 the slides J are four sets of rollers s around

which pass the ropes l and l' . These ropes are looped and pass around sheaves s' on a cross head S secured to the lower portion of the plunger K . The ropes l, l' pass around the sheaves s^2, s^3 respectively, and around sheaves s^4 at the opposite side of the machine and down to sheaves s^5, s^6 respectively, and are attached to rods mounted in spring boxes S' . The sheaves s^6 are mounted on a hollow weight L , while the sheaves s^5 are 70 mounted on a weight L' adapted to rest within the weight L . Both of these weights are preferably hollow and can be filled to properly balance the plungers and rolls. When it is desired to move the rolls in unison then a pin l^2 is inserted in the openings in both weights so as to attach them together, but by simply drawing this pin each weight will move independently. 80

It will be noticed on referring to Fig. 16, 85 that I preferably make the cutting edge of the knife h' on the head H' curved so that it will make a shear cut when moved past the blade on the head e^3 , thus making it easier to operate than where the two blades 90 are perfectly straight.

While I prefer to mount the pin e on the lower head E , as shown in the drawings, and provide an opening for the insertion of the pin in the head H' , I may in some instances secure the pin in the head H' and allow it to project into the opening in the lower head E . The pin will center the plate if mounted in either head, but in some instances the pin may be dispensed with. 100

In the diagram, Fig. 18, I have shown the four rollers k', g', p^3 and n^2 all in line to illustrate that the paths of the three rolls which form the dish overlap each other while the roller n^2 holds the plate down upon the flange of the dished former and the head G holds the center of the plate also down upon the former, thus making a continuous pressure upon the center of the plate to its edge. The overlapping of the paths 105 of the rolls prevents the creasing of the plate to a considerable extent and when the mechanism is properly operated there will be no buckling and the plate will be perfectly dished. 110

The invention is particularly adapted for dishing large plates, such as plates 8 feet in diameter with a depth of dish at least 30 inches, and these plates have been successfully dished on a machine constructed in 120 accordance with my invention.

The operation is as follows:—The plate to be dished is first cut circular and a hole is punched in its center, it is then heated to the proper degree in a suitable furnace. The central head E' is preferably raised so that it is on a line with the flange d of the dished former D , then the plate is taken from the furnace and placed so that the pin e will project through the hole in the plate and the 125 130

plate will rest upon the head E' and the flange d of the former. The machine is then set in motion, the dished former is rotated with the plate and then the rolls k' 5 are lowered in contact with the plate, pressing upon the plate near the periphery, as indicated in Fig. 7; the head G pressing the central portion of the plate at the same time pressure is applied to the head E', but by 10 having a greater pressure on the head G both heads are forced down and the plate is firmly clamped between the two heads. In the meantime the rolls n² are lowered and raised at intervals so as to hold the edge of 15 the plate down onto the flange of the former as the metal is drawn, otherwise if the plate is not held down as it is drawn the edges will flare and buckle.

When the plate is partially dished I preferably reheat it and in doing so I simply 20 lift the rollers k' and the head G out of contact with the plate, raising the central plate E' and lifting the plate clear of the former when it is transferred from the machine and reheated in the furnace. After 25 reheating it is brought again to the machine and placed on the head E', which is lowered and both the rollers k' and g' are brought in contact with the plate and the heads E' and G are moved downward as 30 the dish is formed. As shown in Fig. 8 both the rolls k' and g' simply rotate upon their axes, while the former D, with the plate, rotates rapidly around the center. 35 When the dish is almost finished the rollers p³ press against the plate near its periphery so as to prevent buckling as the metal is drawn into the former, as at this point the rolls n² lose control of the plate. 40 After the plate is completely dished, as shown in Fig. 9, and it is desired to perforate and flange the dished plate then the cutter H' is brought down onto the plate, making a shear cut through the plate, the 45 opening conforming to the shape of the cutter H and the head e², Fig. 10. The cylinder for actuating the cutter, being carried by the upper plunger, the plate can be cut at any point in the stroke. As the 50 movement of the cutter head continues the rounded edge h² is forced into the portion of the plate overhanging the ring e⁴ and thus the flange is bent outward as indicated in Figs. 11 and 12, although in some 55 instances it will not be necessary or desirable to make an opening and flange the plate and, in some cases, it will only be necessary to make an opening in the plate. The flanged plate is then raised out of the 60 former by simply elevating the head E', backing off the rollers, the head G and elevating the head G', after which it can be readily removed from the machine and the 65 operation can then be repeated upon another plate.

In order to supply water to the cylinder F³, I connect the cylinder to a fixed tubular supply pipe V, Fig. 13, and run a tube v through this pipe, connecting the top end of the tube with a branch leading from the cylinder F³. The tube v has an opening v' 70 communicating with the tubular supply pipe V, so that the cylinder F can be raised and lowered and yet the supply of water to the cylinder will not be interrupted. 75

In Fig. 20, I have shown the flange d of the former D provided with a series of grooves in its upper surface, so that any scale that should collect on the flange will pass into the grooves, thus insuring an even 80 surface for the plate to rest upon.

In the specification I have alluded to the pin as centering the plate, but this is not absolutely necessary and is only used when it is immaterial whether a plate is perforated or not. By utilizing the pin I save 85 time in centering, but the plate may be centered by special rollers n⁴ carried by the radially movable carriages, or may be centered by the roller p³, as noted above. The 90 centering pin, however, is useful in bringing the cutters of the upper and lower dies in alinement so as to insure a clean cut when a hole is to be cut in a plate, but the pin may be dispensed with in this instance 95 where the two parts are accurately fitted.

The rollers carried by the plungers and head may be arranged in a different manner from that shown, one roller may be independent of the other and arranged at a 100 greater distance from the center than the other, and the vertically arranged rollers may be of different shapes, depending upon the character of work to be produced by the machine.

The process herein described forms the subject of a separate application for patent filed by me on the 20th day of May 1908, Serial No. 433,866.

I claim:—

1. The combination of a dished former, means for rotating the former, a central plunger, rolls carried by the central plunger, a plunger situated at one side of the center and carrying a swiveled roll, the path of 115 the swiveled roll overlapping the path of the central plunger, and means for raising and lowering both plungers.

2. The combination of a dished former, means for rotating the former, a central 120 plunger mounted above the former and carrying a head arranged to press upon the plate to be dished and also carrying two pressure rolls, two plungers, one on each side of the central plunger, each plunger 125 carrying swiveled rolls, and means for raising and lowering the several plungers.

3. The combination in a machine for dishing plates of a rotatable dished former, upper and lower clamping heads for clamp- 130

ing the plate and forcing it into the former, said heads being free to rotate with the former, with rollers acting on the plate simultaneously with the movement of the heads, so that the upper head and the rollers press the plate against the former.

4. The combination in a plate dishing machine, of a former, two clamping heads between which the plate is clamped, means for exerting a pressure on the lower clamping head, means for exerting a greater pressure on the upper clamping head so as to force the plate into the former and rolls arranged at different points from the center to press the plate against the former and means for rotating the former.

5. The combination in a dished former having a flange, of a series of rolls mounted above the flange, means for adjusting the rolls so as to cause them to press down upon the plate supported by the flange, a series of pressure rolls, means for raising and lowering said rolls to dish the plate, and vertically arranged rolls for pressing out the buckle as it is formed.

6. The combination of a dished former, means for rotating the former, a central plunger, a roll carried thereby and arranged to bear upon the plate near its center, a plunger at one side of the central plunger, and a swivel roll carried thereby and arranged to bear upon the plate outside the path of the first mentioned roll.

7. The combination of a dished former, means for rotating the former, said former having a flange, a central plunger, one or more rolls carried by the plunger and arranged to bear upon the plate near the center, two plungers mounted on each side of the central plunger, swivel rolls carried by said plungers and arranged to bear upon the plate outside of the path of the first mentioned pair of rolls, a series of vertically arranged rolls adapted to bear upon the edge of the plate and prevent buckling, and a series of rolls adapted to bear upon the plate as it rests upon the flange.

8. The combination of a dished former, means for rotating the former, a central plunger, a head carried by the plunger and adapted to bear upon the center of the plate to be dished and to freely rotate with the plate, and rolls carried by the plunger and arranged to bear upon the plate.

9. The combination of a dished former, means for rotating the former, a vertically movable central head mounted in the former and adapted to be raised even with the upper edge of the former, a plunger centrally mounted above the former, a head swiveled upon the plunger and adapted to be rotated with the former when the plate is clamped between the head and the former, and means for pressing the plate into the former.

10. The combination of a former, means for rotating the former, a central head mounted within the former, a rod extending from the head down through the shaft of the former, a plunger on the rod, a cylinder in which the plunger is mounted, a plunger mounted above the former and having a head at its lower end, a cylinder in which the plunger is mounted, and means for pressing the plate onto the former.

11. The combination of a dished former, a hollow shaft upon which the former is mounted, a bearing for said shaft, means for driving the shaft, a head mounted within the former, a rod extending through the hollow shaft and carrying the head, a plunger mounted on the rod, a cylinder in which the plunger is mounted, said cylinder being carried by the frame of the apparatus, and means for pressing a plate onto the former.

12. The combination in a plate dishing machine, of a central plunger, means for operating the plunger to aid in dishing the plate, a cylinder carried by the plunger, a head in the plunger and a piston in said cylinder connected to the head so that the head can be operated no matter in what position the plunger is in.

13. The combination in a plate dishing machine, of a dished former, a hollow head upon which the former is mounted, a hollow shaft secured to the head, a gear secured to the shaft, a driving shaft having a pinion meshing with the gear, bearings for the said hollow shaft, a rod mounted in the hollow shaft, a head on the upper end of the rod mounted in the hollow supporting head for the dished former, rings on said head, the inner ring forming a portion of the cutter, a cutter mounted on the plunger above the dished former, and means for operating the upper cutter so as to cut an opening in the dished plate.

14. The combination of a dished former, a hollow head supporting the former, a hollow shaft carrying the head, means for driving the shaft, a rod mounted in the hollow shaft, a head carried by the said rod and mounted in the hollow head carrying the former, rings on the said head forming an annular space, a plunger above the former, a head carried by the plunger and having a knife arranged to cut a hole in the plate, the cutter head also having a portion acting as a flanging tool for flanging the head on a continued movement of the cutter head.

15. The combination in a rotating dished former, of a central plunger, rolls carried by the central plunger for acting upon the plate carried by the former, two plungers mounted on each side of the central plunger and having swivel rolls also acting upon the plate, with means for adjusting the side plungers in unison toward and from the central plunger.

16. The combination of a dished former, means for rotating the dished former, a central plunger mounted above the former, rolls carried by the said plunger, plungers at each side of the central plunger, swiveled rollers carried by the side plungers, means for moving the side plungers toward and from the central plunger, and counterbalance mechanism for counterbalancing the side plungers and the rolls.

17. The combination of a dished former, means for rotating the dished former, a central plunger mounted above the former, rolls carried by the said plunger, plungers, at each side of the central plunger, swiveled rollers carried by the side plungers, means for moving the side plungers toward and from the central plunger, and counterbalance means consisting of two sets of ropes passing around the sheaves on the frame and sheaves on the side plungers, with weights suspended from said ropes.

18. The combination of a dished former, means for rotating the dished former, a central plunger mounted above the former, rolls carried by said plunger, plungers at each side of the central plunger, swiveled rollers carried by the side plungers, means for moving the side plungers toward and from the central plunger, counterbalance means consisting of two sets of ropes passing around the sheaves on the frame and sheaves on the side plungers, weights suspended from said ropes, and means for connecting the weights so that they will work as one weight.

19. The combination of a dished former, means for rotating the former, a frame, a cylinder mounted on the frame above the former, a plunger adapted to the cylinder, a head carried by the plunger, rolls also carried by the plunger adapted to press a plate into the former, a cylinder carried by the upper end of the plunger, a rod extending through the plunger, a plunger adapted to the last mentioned cylinder, and a head carried at the lower end of said rod.

20. The combination of a frame, a shaft mounted on the frame, a dished former mounted on the shaft, means for rotating the shaft and the former, a cross beam situated on the frame above the former, a cylinder mounted on the cross beam, a plunger mounted in the cylinder and carrying a head at its lower end and rolls for dishing the plate, two slides mounted on the beams, a screw for adjusting the slides toward and from each other, cylinders carried by the slides, plungers mounted on the cylinders, extensions on the plungers, and swiveled rolls carried by the extensions and also adapted to shape the plate to the former.

21. The combination of a dished and flanged former, means for pressing a plate into the former to dish it, a slide, a carrier mounted on the slide, and a roll mounted

on the carrier and situated directly above the flange of the former so that the roll will hold the plate onto the flange as it is being dished.

22. The combination of a former, means for rotating the former, means for pressing a plate into the former, a series of radially arranged frames, a slide on each frame, a vertically adjustable carrier on each slide, and a roll mounted on each carrier, with means for adjusting the slide and means for adjusting the carrier.

23. The combination of a dished former, means for rotating the former, means for pressing a plate into the former, a series of radially arranged frames, a slide on each frame, two carriers on each slide, one mounted above the other and each independently adjustable in a vertical direction, means for adjusting the slide, and a roller on each carrier, one roller arranged at an angle to the other.

24. The combination of a dished and flanged former, means for rotating the former, rolls for pressing the plate into the former, a series of radial frames, slides adapted to move radially on each frame, a screw mounted on each frame and adapted to move the slides, gearing by which the screws are connected so as to work in unison, a standard on each slide and a standard on each frame back of the slides, upper and lower shafts mounted in bearings on the two standards, two vertical screws in each of the standards of the slides, two carriers mounted on the standards, one carrier carrying a horizontally arranged roller and the other carrying a vertically arranged roller, and vertical screws, one geared to one of the said shafts and the other geared to the other shaft and one adapted to a nut on one carrier and the other adapted to a nut on the other carrier, so that said carriers can be independently adjusted in a vertical direction.

25. The combination in a machine for shaping metal plates, of a former, a cylinder mounted above the former, a plunger in the cylinder, a cylinder carried by the upper end of the plunger, a fixed tubular supply pipe, a bracket projecting from one side of the said movable cylinder, a tube extending from this bracket through the fixed supply pipe, and an opening in the tube so that water under pressure may flow to the cylinder no matter in what position the cylinder is in.

26. The combination in a machine for shaping metal plates, of a former, side cylinders mounted above the former, plungers mounted in the cylinder, two fixed supply pipes mounted on the upper frame of the machine, a tube attached to each cylinder and extending through each tubular supply pipe, an opening in the tube forming com-

munication with the interior of the supply pipe, and means for moving the cylinders toward and from each other.

27. The combination in a machine for shaping metal plates, of a revolving dished former having a flange at its periphery, said flange having a series of annular grooves in its upper surface, means for forcing the plate to be dished into the former and rollers tending to hold the plate on the flange.

28. The combination of a revolving dished former, a clamp revolving with the former and having the lower portion of the clamp forming, when down, a portion of the form-

er, said clamp driving the plate to be dished and capable of moving downward to pull the plate to be dished in the direction of the bottom of the former, and a series of rollers pressing on different portions of the plate 20 at the same time between the clamp and the top of the former to press the plate into the former.

In testimony whereof, I have signed my name to this specification, in the presence of 25 two subscribing witnesses.

JOHN S. WORTH.
